UNITED STATES PATENT OFFICE.

EDWARD D. CANDEE, OF BROOKLYN, NEW YORK, ASSIGNOR TO THE
NASHAWANNUCK MANUFACTURING COMPANY, OF EASTHAMPTON,
MASSACHUSETTS.

DESIGN FOR A CLASP FOR GARMENT-SUPPORTERS.

SPECIFICATION forming part of Design No. 23,332, dated June 5, 1894.

Application filed April 6, 1894. Serial No. 506,637. Term of patent 3½ years.

To all whom it may concern:

Be it known that I, EDWARD D. CANDEE, a citizen of United States, residing at Brooklyn, in the county of Kings and State of New York, 5 have invented and produced a new and original Design for a Clasp for Garment-Supporters; and I do declare the following to be a full, clear, and exact description of the same, reference being had to the accompanying 10 drawing, forming a part thereof.

The figure is a perspective of a clasp for garment supporters illustrating my novel design.

The leading feature of my design consists 15 of a clasp for garment supporters of peculiar configuration which comprises the back plate

1 the lower portion of which is made fan shaped as at 2 and the clamping plate 3 the lower portion of which is made fan shaped as at 4.

Having thus described my invention, I claim—

The design for configuration of a drawer supporter clasp substantially as herein shown and described.

In testimony whereof I affix my signature in presence of two witnesses.

EDWARD D. CANDEE.
